UNITED STATES PATENT OFFICE.

SIMS LEVER, OF SYDNEY, NEW SOUTH WALES, AUSTRALIA.

AUTOMATIC EXTINGUISHER FOR LAMP-BURNERS.

No. 800,310.

Specification of Letters Patent.

Patented Sept. 26, 1905.

Application filed April 22, 1904. Serial No. 204,483.

To all whom it may concern:

Be it known that I, SIMS LEVER, dental surgeon, a subject of the King of Great Britain, residing at No. 177 Macquarie street, 5 Sydney, in the State of New South Wales and Commonwealth of Australia, have invented a new and useful Improved Automatic Extinguisher for Lamp-Burners, of which the following is a specification.

10 This invention relates to improved attachment to oil, oil-gas, and the like burners for automatically extinguishing such burners in case of overthrow or other accident, and though it has been specially devised for application to the burners of hand-lamps it may also be applied to any burners, fixed or otherwise, where there is danger from accident or jar which will cause ignition of escaping oil or other fuel or other material by the flame 20 of said burner suffering the accident or jar.

This improved attachment to oil, oil-gas, and the like burners for automatically extinguishing such burners in case of overthrow or other accident consists, essentially, in detachable lever or radius-bar with the turn-screw of the wick or fuel-supply tube, a weighted ball, a circular seating for said weighted ball of smaller size than the diameter of said ball, and a chain or cord connecting the said detachable radius-bar through said seating to the weighted ball, arranged that as the weighted ball falls from the seating, which it is adapted to do on the tilting or overthrow of the burner or on the jarring 30 of the same, it pulls upon the chain and by means of the radius-bar turns the adjusting-screw and diminishes the height of the wick in the burner-tube, and so extinguishes it. The radius-bar in other arrangements by its motion will turn the cock or tap of the fuel-supply tube, and thus extinguish the burner.

As an illustration of the application of this invention to the best use the same will now be described with reference to the drawings 45 herewith, in which—

Figure 1 is an elevation of the burner of an ordinary oil-lamp having these improved attachments; and Fig. 2 is a reverse sectional plan of the same, taken on the line 2 in 50 Fig. 1.

The turn-screw end 3 in this case is a hol-

low bulb, and it has orifices 4 through it across the center, adapted to receive a slightly-tapered lever or radius rod or needle 5 and allow said needle 5 to be easily and quickly detached for rearrangement of the wick as to its height in the wick-tube. Instead of a needle end passing this orifice in the turn-screw end this inner end of the needle-bar might be a clip or spring catch to take firmly over the end edgewise or over the stem. To the outer end of this needle 5 is attached a chain 6, reaching through a guiding-eye 7 and upwardly through circular seating 8 to the weighted ball 9, which seating 8 is considerably smaller than said ball 9. The eye 7 and the seating 8 are affixed to the burner in any well-known manner. As shown in the drawings, they are brazed or soldered thereon. The slight taper of needle 5 prevents it from passing too far through the pair of orifices 4, in which it is inserted after the wick is adjusted. The slack of chain 6 allows of regulation as to height of wick within all necessary limits, and it is needful only occasionally to detach and reenter the needle 5 in the turn-screw end 3. The ball 9 merely rests uncontrolled thereby on the seating 8 and will fall therefrom on sensible jar or upon tilting or overthrow of the lamp or burner. 8c As said ball 9 leaves said seating 8 its weight sharply pulls the chain, and this draws the needle 5 over, and this movement revolving turn-screw 3 at once lowers the wick in the wick-tube and extinguishes the flame. When 85 the seating 8 is not hollow, as shown, the eye 7 is an essential, but when said seating is hollow it acts as a guide for the chain and the eye 7 may be dispensed with. The ball 9 being so very heavy comparatively will cause 90 this extinguishing of the lamp practically before the burner or the reservoir reaches the lower surface, where it may break and will certainly do so before lodgment should the lamp be thrown or be jarred or jerked to any 95 distance.

Having now particularly described and ascertained the nature of my said invention and in what manner the same is to be performed, I declare that what I claim is—

100 In combination with a burner, a turn-screw for regulating the wick, said screw having an

enlarged substantially cylindrical head having transverse orifices therein, a needle adapted to loosely fit in said orifices, a chain secured to one end of said pin, a seating secured to the burner and a weighted ball resting in said seating and being attached to the other end of the chain.

In testimony whereof I have signed my name to this specification in the presence of two subscribing witnesses.

SIMS LEVER.
